ABSTRACT OF THE DISCLOSURE

A piston for a barrel engine having a reduced diameter portion adaptable for reciprocating in a cylinder and having an enlarged diameter portion having first and second rollers attached thereto which are engageable with the top and bottom sides, respectively, of a harmonic cam on an output shaft. Guide shoes attached to the cylinder slidably engage a longitudinal slot in the enlarged diameter portion of the piston to prevent rotation of the piston.

The following pending applications of applicant are related to the present disclosure:

- (a) Application Ser. No. 538,162, filed Mar. 22, 1966, for "Sealing Device for High Temperature Input Nozzle";
- (b) Application Ser. No. 546,150, filed Apr. 26, 1966, for "Barrel Engine Having Cooling System"; and
- (c) Application Ser. No. 547,080, filed Apr. 29, 1966, now Patent No. 3,359,864, for "Barrel Engine Having Forced Lubrication."

Background of the invention

The present invention relates to improved pistons for a barrel engine. A barrel engine is an engine that has a plurality of pistons having their stroke axes parallel to and symmetrically disposed to a power output shaft. The pistons coat with cam means on the output shaft so as to convert the reciprocating motion of the pistons into rotary motion which rotates the output shaft. Barrel engines may find application in many fields both commercial and military, and one important military application for a barrel engine is that of a propulsion unit for Naval torpedoes.

One heretofore known barrel engine specifically adaptable for use as a prime mover for Naval torpedoes is disclosed in the present inventor's U.S. Patent 3,151,527, entitled "Barrel Engine," which issued Oct. 6, 1964. In this patent, there is disclosed a barrel engine having torque balanced contra-rotating propellers for propelling a torpedo through water. Torque balance is required since a lack of it would impose a resisting torque on the torpedo body and cause the torpedo to roll to one side. A permanent inclination of the torpedo is very undesirable as it will interfere with the steering controls. An outer housing and a hollow inner shaft are coaxially mounted relative to each other and adapted to establish relative rotation. A fluid pressure inlet, through which hot gas flows, is positioned coaxially with respect to the inner shaft. The motive power assembly includes a plurality of pistons reciprocally mounted in the housing with their stroke axes parallel to the axial center of rotation. The motive power assembly is constructed and arranged to translate the fluid pressure into an axial force component. A wobble plate conversion assembly is mounted to the inner shaft for converting the reciprocatory substantially linear motion of the pistons into rotary motion. The outer housing is rotated in an opposite direction to the inner shaft solely by virtue of the reaction to the rotation of the inner shaft.

In applicant's above-identified patent, a cylindrical piston is provided with a suitable annular dimension to

2

slide within a cylinder casing. The piston has an integrated socket joint receiving a sphere-like end of a piston rod member which connects the piston to a swashplate ring by way of a ball end portion which is received in a bronze ball socket joint. The outer cylindrical surface of the piston has a number of annular grooves which receive a metallic or plastic ring and one groove is adapted to receive an O-ring which serves to lend a certain degree of radial resiliency to the reciprocating piston member.

Summary of the invention

The present invention relates to an improvement in barrel engines of the type shown in the inventor's U.S. Patent 3,151,527, and while the principle of operation is essentially identical, there are some structural differences. For example, the swashplate cam of the patent, which serves to convert the reciprocating motion of the pistons to rotary motion which turns the inner tubular power take-off shaft, has been replaced by a harmonic cam.

The specific improvement for a barrel engine to which this disclosure relates is that of the pistons which drive the harmonic cam which is attached to an inner output shaft. The piston has a reduced diameter portion that slides in a cylinder, and this reduced diameter portion is provided with a plurality of grooves which are adapted to receive piston rings. An enlarged diameter portion of the piston is provided with a longitudinal slot and a first roller is positioned in the slot and rotatably mounted on a shaft which is attached to the enlarged diameter portion. A second roller is attached to the enlarged diameter portion of the piston, and the first roller transmits a heavy axial load imposed upon the reduced diameter portion of the piston by the working fluid to a harmonic cam which is attached to an output shaft. The second roller engages the backside of the harmonic cam and serves to hold the piston against inertia force during the exhaust stroke. A pair of guide shoes are provided on the cylinder walls and these guide shoe slidably engage with the longitudinal slot in the enlarged diameter portion to prevent rotation of the piston.

It is therefore a general object of the present invention to provide in a barrel engine an improved mechanism for converting linear motion to rotary motion by providing improved pistons which co-operate with a harmonic cam.

Other objects and advantages of the present invention will be readily appreciated as the same becomes better understood by reference to the following detailed description when considered in connection with the accompanying drawings.

Brief description of the drawings

FIGURE 1 is a partial longitudinal sectional view showing an aft section of a torpedo which embodies the present invention;

FIGURE 2 is a partial longitudinal sectional view of a barrel engine embodying the present invention;

FIGURE 3 is a sectional view of a piston and a piston liner; and

FIGURE 4 is a sectional view taken on line 4—4 of FIGURE 3.

Description of the preferred embodiment

Referring now to the drawings, and particularly to FIGURE 1, there is shown an aft section of a torpedo housing 11 in which a barrel engine 12 drives a pair of contrarotating propellers 13 and 14. Hot gas, or other suitable fluid, flows from a combustion chamber into barrel engine 12 where it is distributed to a plurality of cylinders by a rotary valve assembly. By way of example, the hot gas, or other suitable fluid, may flow from a combustion chamber into a tubular conduit and a hot gas seal assembly, as shown in applicant's co-pending patent ap-

application entitled, "Sealing Device for high Temperature Input Nozzle," which was filed Mar. 22, 1966, Ser. No. 538,162. The hot gas enters into a rotary valve assembly which distributes the hot gas to the various cylinders.

The hot gas, or other suitable fluid, which is distributed by the rotary valve assembly to the various cylinders, drives pistons in the cylinders and the reciprocating motion of the pistons is converted into rotary motion by means of a cam that is attached to and drives a hollow shaft 15. Propeller 13 is attached on the end of hollow shaft 15 and is rotated thereby, and a second hollow shaft 16 is concentrically mounted around hollow shaft 15 and is driven in a contra-rotating direction relative to the direction of rotation of hollow shaft 15. The reciprocatory linear motion of the pistons is converted, by the cam, into rotary motion which rotates the inner hollow shaft 15 and, simultaneously, torque reaction causes the outer hollow shaft 16 to be contrarotated, as shaft 16 is substantially integral with the housing of barrel engine 12. Propeller 14 is attached to the outer end of hollow shaft 16 and thus rotates in a contrarotating direction relative to the direction of rotation of propeller 13.

Referring now to FIGURE 2 of the drawings, hollow shaft 15 is rotatably mounted within a housing by means of radial bearing 17 and thrust bearing 18. The housing is comprised of a front section 19 which is attached to an aft section 21 by means of bolts 22. By way of example, front section 19 might be comprised of a monolithic block of cast aluminum. A cam 23 is attached to hollow shaft 15 by key 24, and rotation of cam 23 causes a corresponding rotation of hollow shaft 15. A rotary valve 25, having an inlet port 26 and an exhaust port 27, is rotatably mounted in front housing section 19 and is attached to the inner end of hollow shaft 15. Exhaust port 27 communicates with the bore of hollow shaft 15 and exhaust products passing through port 27 pass into hollow shaft 15 and then are expelled into the air, or into the sea.

A plurality of cylinder liners 28 are seated one each in a plurality of cylinder bores 29 and a reduced diameter portion 31 of a piston 32 is slidably mounted in each liner 28. A second liner 33 is also seated in each cylinder bore 29 and the enlarged diameter portion 34 of piston 32 slides in liner 33. As shown in FIGURES 2, 3, and 4 of the drawings, the enlarged diameter portion 34 of piston 32 is provided with a longitudinal slot 35 that divides enlarged diameter portion 34 into two legs 36 and 37, with leg 37 being longer than leg 36. A main roller 38 is positioned in slot 35 on shaft 39 that is fitted in legs 36 and 37. Spacers 41 and 42 are provided to reduce end play of roller 38. A second roller 43 is attached to leg 37 by means of shaft 44 and nut 45. Main roller 38 engages the front cam surface 46 of cam 23, and provides the driving force from piston 32 to rotate shaft 15. The second roller 43 engages the back cam surface 47 of cam 23 and holds piston 32 against inertia forces during the exhaust stroke.

As best shown in FIGURES 3 and 4 of the drawings, a pair of guide shoes 48 and 49 are attached to liner 33 to prevent piston 32 from rotating. The width of guide shoes 48 and 49 is such that the guide shoes slidably engage with slot 35 in piston 32. One side of each guide shoe is shaped to fit the curvature of liner 33 and guide shoes 48 and 49 are attached to liner 33, by way of example, with screws 51. The reduced diameter portion 31 of piston 32 is provided with grooves 52 which retain piston rings 53.

In operation, hot gases enter rotary valve 25 from a stationary nozzle and these hot gases are selectively distributed to the various cylinders at an appropriate time when pistons 32 are in a position to make a stroke. The hot gases impinge on the end of reduced diameter portion 31 of piston 32 and move the piston outwardly. The

straight line motion of pistons 32 is converted to rotary motion by means of roller 38 which engages with the front cam surface 46 of cam 23. As cam 23 is keyed to shaft 15, rotation of cam 23 causes shaft 15 to be rotated in one direction, and shaft 16 is rotated in a contra-rotating direction due to torque reaction as more fully explained by applicant's U.S. Patent 3,151,527, entitled, "Barrel Engine," which issued Oct. 6, 1964.

It can thus be seen that the present invention provides an improved piston and cam arrangement for rotating a shaft of a barrel engine. Obviously many modifications and variations of the present invention are possible in the light of the above teachings. It is therefore to be understood, that the invention may be practiced otherwise than as specifically described.

I claim:

1. In a barrel engine having a housing, a hollow shaft rotatably mounted within said housing, a plurality of cylinder bores in said housing extending in circular array about said hollow shaft with their axes parallel thereto, said cylinder bores each having a reduced diameter portion and an enlarged diameter portion, and a harmonic cam attached to said hollow shaft, said harmonic cam having front and back cam surfaces, the improvement comprising:
  - a plurality of pistons mounted one each in each said cylinder bore, each said piston having a reduced diameter portion and an enlarged diameter portion respectively mounted in the reduced diameter portion and enlarged diameter portion of each said cylinder bore,
  - first and second rollers attached to each said enlarged diameter portion of each said piston, said first roller being engaged with said front cam surface and said second roller being engaged with said back cam surface,
  - said enlarged diameter portion of each said piston has a longitudinal slot extending substantially the entire length thereof whereby first and second legs are formed and wherein said first roller is rotatably attached to said first and second legs in said longitudinal slot and wherein said second roller is rotatably attached to only said first leg, and
  - a pair of oppositely disposed guide shoes slidably engage with said longitudinal slot of each said enlarged diameter portion, said guide shoes being attached inside said cylinder bores.
2. In a barrel engine as set forth in claim 1 wherein each said reduced diameter portion of each said piston is provided with a plurality of grooves adaptable for receiving sealing rings.
